UNITED STATES PATENT OFFICE.

EDWARD THOMAS, OF NEW YORK, N. Y., ASSIGNOR TO UNDERWOOD TYPEWRITER COMPANY, OF NEW YORK, N. Y., A CORPORATION OF DELAWARE.

TYPEWRITING-MACHINE.

1,370,243.

Specification of Letters Patent.

Patented Mar. 1, 1921.

Application filed June 20, 1919. Serial No. 305,497.

To all whom it may concern:

Be it known that I, EDWARD THOMAS, a citizen of the United States, residing in New York city, in the county of New York and 5 State of New York, have invented certain new and useful Improvements in Typewriting-Machines, of which the following is a specification.

This invention relates to typewriting machines, and is herein illustrated as applied to the machines known as continuous fan-fold billing machines, although such latter machines are not used exclusively for fan-fold webs, or exclusively for billing.

15 In such fan-fold machines and in other machines, it would be frequently advantageous to be able to insert a work-sheet from the front of the machine around the platen passing it outside of a work-sheet or work-sheets, which may already be in the machine.

It has been found, however, difficult and almost impossible to insert short, separate work-sheets in this fashion, because there is great liability of their catching upon either 25 the paper-apron or upon the feed-rolls or other parts beneath the platen. This liability of catching, added to the friction against the webs or work-sheets already in the machine, has practically prohibited the 30 general utilization of short work-sheets in these machines.

According to the present invention, the platen of the typewriting machine may be raised to a sheet-inserting position completely clear of the feed-rolls and other parts, and, while detained in such raised position, the short work-sheet may be readily inserted from the front, and after the work-sheet is thus inserted, the platen 40 may be dropped back against the feed-rolls and the writing proceed as usual. In order to keep the inserted work-sheet clear of the feed-rolls and other obstructing parts, means may be provided which will form a fairly 45 smooth surface for the work-sheet to slide over, and may be adapted to bend it rearwardly and somewhat upwardly as it slips around the platen. As herein illustrated, such means include guides which normally 50 lie out of use adjacent the paper-table, but which, when the platen is swung upwardly,

rise to a guiding position. In order to enable the typist to have both hands free while inserting the work-sheet, there may be provided a handle or finger-piece which is 55 adapted to be actuated to raise the platen to the sheet-inserting point or position, and to detain it there when so raised. Where the invention is applied to a fan-fold billing machine of the type above described, the 60 connections may be such that the usual displacement or swinging of the platen, by which the front paper-table is brought to a horizontal position, will not be interfered with.

In order to facilitate the insertion of the outside sheet, the usual knife for severing the fan-fold sheets may be caused to swing rearwardly and downwardly toward the sheet-guide which rises from the paper-table, 70 so that the knife assists in forming a continuous guide to carry the inserted sheet around the platen.

Other features and advantages will hereinafter appear.

In the accompanying drawings,

Figure 1 is a fragmentary sectional side view of a fan-fold typewriting machine, showing the present invention as applied thereto.

Fig. 2 is a view similar to Fig. 1, but omitting a number of parts, and showing the handle, which swings up the platen, actuated far enough to release the usual platen-swing-frame of the fan-fold machine. 85

Fig. 3 is a view similar to Fig. 2, but showing the handle actuated far enough to have lifted the platen and latched it in its intermediate sheet-inserting raised position.

Fig. 4 is a view similar to Fig. 1, omitting 90 many parts, but showing the swing frame swung up in the usual gaging operation of a fan-fold billing machine.

Fig. 5 is a perspective view of most of the parts seen in Fig. 1, and including a few 95 other parts of the typewriter.

Fig. 6 is a front view of the right-hand end of the parts seen in Fig. 5.

Fig. 7 is a perspective view of the sheet-guide for guiding the inserted work-sheet 100 rearwardly and upwardly.

Fig. 8 is a perspective view of the rear or

bottom paper-table or apron, showing the depressions for accommodating the guide of Fig. 7.

In the usual fan-fold billing machine, a 5 web 10, herein shown as comprising three plies or layers, is drawn forwardly over the rear bar 11 of the usual extension 12 of the typewriter carriage. Upon this extension runs the usual carbon-paper carriage 13 10 having clip bars 14 for carbon-sheets 15, which are interleaved between the layers of the web 10.

In the ordinary operation of gaging a web 10 upon the machine, the platen 16 is 15 swung upwardly to the Fig. 4 position, by first pushing rearwardly a handle 17 to release a catch 18 overlying a holding roll or pin 19 upon a swing frame 20. When the swing frame 20 is thus released, the typist 20 usually seizes the upstanding extension 21 of the front paper-table 22, which forms part of the swing frame, and swings the swing frame forwardly to the Fig. 4 position, so that it rests upon the support 21^a, 25 and then draws forwardly upon the webs 10, gaging them against the usual adjustable end gage 23 upon the extension 21. While holding the webs thus gaged, the typist usually pushes the carbon-paper carriage 13 30 rearwardly by the usual handle, not shown, and then swings the swing frame rearwardly to carry the platen 16 against the usual rear feed-rolls 24 and front feed-rolls 25. Usually after this the typist severs the 35 gaged web by drawing it against the knife 26, and then proceeds to write by actuating the types 27 to print upon the platen on the usual printing line.

According to the present disclosure of 40 my invention, the platen may be lifted to an intermediate sheet-inserting position and held there. For this purpose, there is provided a handle 28 which normally occupies the Fig. 1 position, and which is adapted to 45 be drawn forward, swinging it around its journal 29 in the side piece 30 of the swing frame 20. This swinging of the handle carries around with it a cam follower arm 30^a, having a follower pin or roll 31, which 50 underlies a cam 32 fast upon the rod or shaft 33, which carries the swing frame hook or catch 18 at each end of the swing frame. When the handle 28 is drawn forward to the Fig. 2 position, in which it is shown as sub- 55 stantially upright, it has completely released the hooks 18, and is detained at this angle upon the swing frame 20, because a spring detent 34 seats itself in a depression 35 in the hub 36, which is fast to the handle 60 28. In swinging to this position, the handle 28 also swings rearwardly an extension 37 of the follower arm or plate 30^a, and causes a pin 38 therein to draw rearwardly a link 39, which has a slot 40, against the rear end 65 of which the pin 38 normally rests. In

thus drawing the link 39, the link swings downwardly the knife 26 from the Fig. 1 to the Fig. 2 position, thus carrying the knife backwardly along the webs if they have been previously severed, and preventing them from slipping out of place during the ensuing rising of the platen. The connections for doing this include a pivoted arm 41 to which the link 39 is pivoted, said arm carrying at its end a cam pin 42, which 70 rides in a cam slot 43 of a plate 44 forming a lever journaled on the platen axle 45, and carrying at its front end 46 the knife 26. Further forward drawing of the handle 28 causes the pin 42 to strike the rear end 47 80 of its cam slot 43, as in Fig. 2, with the result that the handle 28 draws on the plate 44 and positively swings the swing frame 20 and the platen upward until they reach the Fig. 3 position, at which position the swing 85 frame is detained because a rear arm 48 thereon carries its detent 49 into the depression 50 of a supporting spring 51, said spring being strong enough to hold the swing frame in this upper position, with the platen 16 90 now at its intermediate sheet-inserting point or position. In this position the platen 16 is above and clear of the printing point indicated by the type-head 27, and is therefore above and clear of the usual front co- 95 operating elements (not shown), such as the usual type-guide and ribbon-vibrator and ribbon, thereby providing a clearance for the insertion of a work-sheet backwardly from the front down at the front of and around 100 below the platen.

When the parts are in this position, the typist has both hands free and may hold (Fig. 3) the webs 10 with the thumb or finger against the front of the platen or 105 now substantially vertical front paper-table 22, while inserting with the other hand a front sheet 52 and an associated carbon 53. The sheet 52 and carbon 53 slip down and are guided by the inner side of the 110 knife 26 and then strike against the curved surface of a paper-guide 54 which includes arms or fingers 55 normally lying within openings or depressions 56 of the curved rear paper-table or bottom 115 paper-apron 57, as in Fig. 1, but which are swung up to the Fig. 3 position by the rising of the platen. The connections for causing the rising of the fingers 55 include a link 58, which is pivoted to a hub 59 of 120 the swing frame where it is journaled upon the usual rod or shaft 60, said link including an elbow 61 to curve over the usual pinion 62, and also including a rearwardly-extending stretch 63 which is pivoted to the guide 125 54 at an ear 64. The forward swinging of the swing frame swings the pivot 65 of the link 58 forwardly and thereby draws on the ear 64, thus rocking the arms 55 upwardly because they spring from a bail or cross- 130

piece 66 lying below the rod 33 and journaled thereon by ears 68 at the top thereof. The arms 55 extend forward through an opening 69 in the rear paper-table 57, as appears in Figs. 1, 2, 3 and 4. The pivot 65 is far enough from the axis of the shaft 60 to swing the arms 55 up so that they will just contact with the knife 26, as seen at Fig. 3.

10 The angle between the knife 26 and the arms 55 is so slight that the front sheet 52, which is being inserted, readily bends rearwardly and slides rearwardly upon the arms 55 and slips into the opening 69 in the apron 57, so that it is carried beneath the rod 33 and, therefore, is not liable to be doubled up by the friction of the web 10, as might occur if it were attempted to thrust the sheet between the webs 10 and the usual cover 15 plate 70 which overlies the rod or bar 33.

In order to make sure that the sheet 52 when thus thrust rearwardly will pass beneath the rod 33, the usual cover plate 70 is provided with a forwardly-extending 20 plate 71, against which the webs 10 may lie normally, and which carries a deflecting underpiece 72, which bends the sheet 52 slightly downwardly if necessary to cause it to pass beneath the rod 33. The apron 57, 25 the cover plate 70 and its extension 71 are shown in the drawings as formed in a single piece.

When the sheet 52 has thus been inserted, it may be gaged against an adjustable side 30 gage 73 upon the front paper-table. If it be desired to separately gage the end of the inserted sheet 52, the work-sheets and the webs 10, instead of being gaged, as in Fig. 4, may be passed through a slit 74, so that they pass 35 behind the front table 22, and may be gaged against any suitable gage, while the work-sheet 52 may be gaged against a leading edge gage, not shown, lying upon the work-table, or it may be gaged against the adjustable gage 23, which, for this purpose, may be moved down toward the front paper-table 22.

When the work-sheet 52 has been thus inserted and gaged, the platen may be swung 40 back against the feed-rolls 24 and 25 by a rearward movement of the handle 28, whereupon the hooks 18 will hook it down, being swung forward by the usual spring 75. There may be provided a handle 76 for moving 45 the knife 26 rearwardly and downwardly against the tension of its returning spring 76 without, however, raising the platen. For this purpose, the handle 76 is fast to a short shaft 77, upon which the arm 50 41 is also fast, with the result that actuating the handle 76 will swing the plate 44 and consequently the knife 26.

In order to prevent the handle 28 from rattling or from falling out of position 55 when the swing frame is swung to the Fig.

4 position, the detent spring 34 may normally rest in a depression 78 in the hub 36.

The bottom paper-table 57 may be of much the usual form below the opening 69 except for the depressions 56, and thus accommodate the feed-rolls, which may be substantially of the usual form, but so spaced that the arms 55 may rest upon the rear feed-roll shaft 79.

It will be noted that the arms 55 rise to the 75 Fig. 4 position even if the handle 28 is not actuated, because the swinging of the swing frame 20 lifts them. This, however, does not interfere with the threading or drawing forward of the webs 10, as shown in Fig. 4, 80 since the arms 55 lie far below the webs 10. The pinion 62 forms part of the connection of the line-space handle 80 to the platen 16, one form of said connection being disclosed in the patent to Wernery & Smith, No. 85 1,132,055, dated March 16, 1915.

Owing to the slack created in the web 10 by the lifting of the platen, the web will lie upon the fingers 55 when the platen is lifted by the handle 28, and to insert the 90 sheet 52, the web should be lifted by the thumb and finger clear of the fingers 55, as is shown in Fig. 3. This gives the sheet 52 a free path to the opening below the deflector 72 and above the cross-piece 66, so that it 95 may project beneath the carriage extension 12.

Variations may be resorted to within the scope of the invention, and portions of the improvements may be used without others. 100

Having thus described my invention, I claim:

1. In a typewriting machine, the combination with a platen and platen frame including a rear paper-table, of feed-rolls 105 against which the platen normally bears, a swing frame swingable in said platen frame to carry the platen away from said feed-rolls to enable a web to be drawn horizontally beneath the platen over the table, and a handle adapted to be operated to swing the platen to an intermediate point and cause it to be held there. 110

2. In a typewriting machine, the combination with a platen and platen frame including a rear paper-table, of feed-rolls 115 against which the platen normally bears, a swing frame swingable in said platen frame to carry the platen away from said feed-rolls to enable a web to be drawn horizontally beneath the platen over the table, a handle adapted to be operated to swing the platen to an intermediate point and cause it to be held there, and a guide to turn backwardly under the platen a sheet inserted in 120 front of the web. 125

3. In a typewriting machine, the combination with a platen and platen frame including a rear paper-table, of feed-rolls 130 against which the platen normally bears, a

swing frame swingable in said platen frame to carry the platen away from said feed-rolls to enable a web to be drawn horizontally beneath the platen over the table, a handle adapted to be operated to swing the platen to an intermediate point and cause it to be held there, a guide to turn backwardly under the platen a sheet inserted in front of the web, and a guide for the web behind the platen above the paper-table, and a guide for said sheet adapted to direct it rearwardly clear of and beneath the web.

4. In a typewriting machine, the combination with a platen and platen frame including a rear paper-table, of feed-rolls against which the platen normally bears, a swing frame swingable in said platen frame to carry the platen away from said feed-rolls to enable a web to be drawn horizontally beneath the platen over the table, means normally holding the platen against the rolls, and a handle adapted to be operated to release the swing frame and then swing the platen to an intermediate point and cause it to be held there.

5. In a typewriting machine, the combination with a platen and a platen frame including a rear paper-table, of feed-rolls against which the platen normally bears, a swing frame swingable in said platen frame to carry the platen away from said rolls, a knife adjacent the platen for severing webs passed around the platen, and a handle for moving said knife away from its cutting position and simultaneously moving the swing frame to lift the platen away from the feed-rolls.

6. In a typewriting machine, the combination with a platen and a platen frame including a rear paper-table, of feed-rolls against which the platen normally bears, a swing frame swingable in said platen frame to carry the platen away from said rolls, a knife adjacent the platen for severing webs passed around the platen, a handle for moving said knife away from its cutting position and simultaneously moving the swing frame to lift the platen away from the feed-rolls, a paper guide normally out of the way beneath the platen, and a connection whereby the handle lifts the guide to the knife to guide backwardly around the platen a sheet inserted at the knife.

7. In a typewriting machine, the combination with a platen and a platen frame including a rear paper-table, of feed-rolls against which the platen normally bears, a swing frame swingable in said platen frame to carry the platen away from said feed-rolls to enable a web to be drawn horizontally beneath the platen over the table, a handle adapted to be operated to swing the platen to an intermediate point and cause it to be held there, a guide normally lying within depressions in said paper-table,

adapted to rise to turn backwardly under the platen a sheet inserted in front of the web, and a connection from said swing frame adapted to raise the guide to effective position.

8. In a typewriting machine, the combination with a platen and a platen frame including a rear paper-table, of feed-rolls against which the platen normally bears, a swing frame swingable in said platen frame to carry the platen away from said feed-rolls to enable a web to be drawn horizontally beneath the platen over the table, a handle adapted to be operated to swing the platen to an intermediate point and cause it to be held there, a guide normally lying within depressions in said paper-table, adapted to rise to turn backwardly under the platen a sheet inserted in front of the web, a connection from said swing frame adapted to raise the guide to effective position, a bar behind the platen above the paper-table over which the web is drawn, and a second guide adapted to guide said sheet beneath said bar.

9. In a typewriting machine, the combination with a platen and a platen frame including a rear paper-table, of feed-rolls against which the platen normally bears, a swing frame swingable in said platen frame to carry the platen away from said feed-rolls to enable a web to be drawn horizontally beneath the platen over the table, a handle adapted to be operated to swing the platen to an intermediate point and cause it to be held there, a guide normally ineffective and lying within openings in said paper-table between the feed-rolls, and adapted to rise and turn backwardly under the platen, a sheet inserted in front of the web, and a link extending from the swing frame to the guide and adapted to raise the guide with the platen, though clear of it.

10. In a typewriting machine, the combination with a platen and a platen frame including a rear paper-table, of feed-rolls against which the platen normally bears, a swing frame swingable in said platen frame to carry the platen away from said feed-rolls to enable a web to be drawn horizontally beneath the platen over the table, a handle adapted to be operated to swing the platen to an intermediate point and cause it to be held there, a guide normally ineffective and lying within openings in said paper-table between the feed-rolls, and adapted to rise and turn backwardly under the platen, a sheet inserted in front of the web, a link extending from the swing frame to the guide and adapted to raise the guide with the platen, though clear of it, a bar behind the platen above the paper-table over which the web is drawn, and a second guide adapted to guide said sheet beneath said bar.

11. In a typewriting machine, the combi-

- nation with a platen and a platen frame including a rear paper-table, of feed-rolls against which the platen normally bears, a swing frame swingable in said platen frame to carry the platen away from said rolls, a knife adjacent the platen for severing webs passed around the platen, a handle for moving said knife away from its cutting position and simultaneously moving the swing frame to lift the platen away from the feed-rolls, and a finger-piece manually operable to independently move the knife away from its cutting position.
12. In a front-strike typewriting machine, the combination with a platen and a platen frame including a rear paper-table, of feed-rolls against which the platen normally bears, a swing frame swingable in said platen frame to carry the platen away from said rolls to enable a web to be drawn horizontally beneath the platen over the table, a guide comprising fingers normally lying against said table, and a link extending from said swing frame and adapted to lift said guide toward horizontal position as the platen rises.
13. In a front-strike typewriting machine, the combination with a platen and a platen frame including a rear paper-table, of feed-rolls against which the platen normally bears, a swing frame swingable in said platen frame to carry the platen away from said rolls to enable a web to be drawn horizontally beneath the platen over the table, a guide comprising fingers normally lying against said table, a link extending from said swing frame and adapted to lift said guide toward horizontal position as the platen rises, and a second guide at the front of the swing frame, adapted to guide a work-sheet onto said first guide when inserted from the front.
14. In a front-strike typewriting machine, the combination with a platen and a platen frame including a rear paper-table, of feed-rolls against which the platen normally bears, a swing frame swingable in said platen frame to carry the platen away from said rolls to enable a web to be drawn horizontally beneath the platen over the table, a support adapted to support said frame when the platen is swung entirely up, and a second support adapted to support said swing frame at an intermediate position.
15. In a front-strike typewriting machine, the combination with a platen and a platen frame including a rear paper-table, of feed-rolls against which the platen normally bears, a swing frame swingable in said platen frame to carry the platen away from said rolls to enable a web to be drawn horizontally beneath the platen over the table, a guide comprising fingers normally lying against said table, a link extending from said swing frame and adapted to lift said
- guide toward horizontal position as the platen rises, a support adapted to support said frame when the platen is swung entirely up, and a second support adapted to support said swing frame at an intermediate position.
16. In a front-strike typewriting machine, the combination with a platen and a platen frame including a rear paper-table, of feed-rolls against which the platen normally bears, a swing frame swingable in said platen frame to carry the platen away from said rolls to enable a web to be drawn horizontally beneath the platen over the table, a guide comprising fingers normally lying against said table, a link extending from said swing frame and adapted to lift said guide toward horizontal position as the platen rises, a second guide at the front of the swing frame adapted to guide a work sheet onto said first guide when inserted from the front, a spring for returning said second guide, a handle for swinging said swing frame, and means co-operating with the handle to hold the second guide in effective position against its spring.
17. In a typewriting machine, the combination with a platen and a platen frame including a rear paper-table, of feed-rolls against which the platen normally bears, a swing frame swingable in said platen frame to carry the platen away from said feed-rolls to enable a web to be drawn horizontally beneath the platen over the table, means normally holding the platen against the rolls, a handle adapted to be operated to release the swing frame and then swing the platen to an intermediate point and cause it to be held there, and a guide to turn backwardly under the platen a sheet inserted in front of the web.
18. In a typewriting machine, the combination with a platen and a platen frame, of feed-rolls against which the platen normally bears, a swing frame forming part of said platen frame to carry the platen up away from the feed-rolls, a hook engageable with the swing frame for normally holding the swing frame to hold the platen against the feed-rolls, and a handle journaled on the swing frame and operable first to release the hook from the swing frame and then to serve as lifting means for the swing frame to carry the platen up away from the feed-rolls.
19. In a typewriting machine, the combination with a platen and a platen frame including a paper-table, of feed-rolls against which the platen normally bears, a swing frame forming part of said platen frame to carry the platen up away from the feed-rolls, a hook normally holding the swing frame to hold the platen against the feed-rolls, a handle journaled on the swing frame adapted to be turned to cam the hook clear of the swing frame and then lift the

swing frame, and a detent for detaining said swing frame with the paper-table substantially vertical.

20. In a typewriting machine, the combination with a platen and a platen frame including a paper-table, of feed-rolls against which the platen normally bears, a swing frame forming part of said platen frame to carry the platen up away from the feed-rolls, 5 a hook normally holding the swing frame to hold the platen against the feed-rolls, a handle journaled on the swing frame adapted to be turned to cam the hook clear of the swing frame and then lift the swing frame, a detent for detaining said swing frame with the paper-table substantially vertical, a rear paper guide over which a web may be drawn around the platen, and a second guide normally in ineffective position, but adapted to rise to effective position 10 to guide a work-sheet inserted from the front beneath said first-named guide.

21. In a typewriting machine, the combination with a traveling carriage and a platen frame therein, of a swing frame in said platen frame, a platen journaled in said swing frame, feed-rolls in the platen frame against which the platen normally bears, a device adapted to hold the swing frame with 25 the platen raised to a considerable degree, a paper table in front of and above the platen adapted to stand nearly vertically when the platen is so raised, and comprising an opening through which a web may be passed to 30 the rear of it, a guide for carrying rearwardly under the platen a work-sheet inserted at the front, and an adjustable edge gage adapted to gage the front inserted work-sheet.

40 22. In a typewriting machine, the combination with a traveling carriage and a platen frame therein, of a swing frame in said platen frame, a platen journaled in said swing frame, feed-rolls in the platen frame against which the platen normally bears, a device adapted to hold the swing frame with the platen raised to a considerable degree, a paper-table in front of and above the platen adapted to stand nearly 45 vertically when the platen is so raised, and comprising an opening through which a web may be passed to the rear of it, a guide for carrying rearwardly under the platen a work-sheet inserted at the front, and an 50 adjustable edge gage adapted to gage the front inserted work-sheet, said guide normally in ineffective position and connected to be drawn to effective position by the swinging of the swing frame.

60 23. In a typewriting machine, the combination with a traveling carriage and a platen frame therein, of a swing frame in said platen frame, a rear guide over which webs may be drawn to the platen and forming part of the platen frame, means for

swinging the swing frame to lift the platen, a rod in said platen frame adjacent said guide, and a paper guide journaled on said rod normally lying in ineffective position beneath the platen, and adapted to be swung 70 to effective position to guide a work-sheet beneath said rod.

24. In a typewriting machine, the combination with a platen and a platen frame, of feed-rolls against which the platen normally bears, a frame displaceable in the platen frame to carry the platen away from the feed-rolls to a position to enable a web to be drawn horizontally beneath the platen, a handle operable to displace the platen to an 75 intermediate position, and means for detaining the platen at said intermediate position.

25. In a typewriting machine, in combination, a rotatable platen, a paper-table below 80 the platen, a paper-guide below the platen independent of the paper-table and normally occupying a position of disuse, and manually operable means for concomitantly raising the platen above the printing point and 85 away from the paper-table and for raising the paper-guide above the paper-table to effective position for turning backwardly under the platen the lower edge of a work-sheet inserted at the front of the platen 90 above the printing point; means being included to automatically return said paper-guide to a position of disuse at the return of the platen to printing position.

26. In a typewriting machine, in combination, a rotatable platen, a rear guide behind the platen over which a web may pass below and around the platen, a paper-table below the platen, a paper-guide below the platen independent of the paper-table and 100 normally occupying a position of disuse, and manually operable means for concomitantly raising the platen above the printing point and away from the paper-table and for raising the paper-guide above the paper-table 105 to effective position for turning backwardly under the platen the lower edge of a work-sheet inserted at the front of the platen above the printing point; means being included to automatically return said paper-guide to a position of disuse at the return 110 of the platen to printing position.

27. In a typewriting machine, in combination, a rotatable platen, a paper-table below the platen, means providing for raising 115 the platen away from the paper-table to enable a web to be drawn horizontally beneath the platen and over the paper-table, manually operable means to raise the platen away from the paper-table to an intermediate sheet-inserting position, a paper-guide below the platen independent of the paper-table and normally occupying a position of disuse, and a connection acting concomitantly with the raising of the platen to the 120 125

- sheet-inserting position to raise the paper-guide away from the paper-table to effective position for turning backwardly under the platen the bottom edge of a sheet inserted in front of the web from the delivery side of the platen; means being included to automatically return said paper-guide to a position of disuse at the return of the platen to printing position.
28. In a typewriting machine, in combination, a rotatable platen, a paper-table below the platen, means providing for raising the platen away from the paper-table to enable a web to be drawn horizontally beneath the platen and over the paper-table, manually operable means to raise the platen away from the paper-table to an intermediate sheet-inserting position, a paper-guide below the platen independent of the paper-table and normally occupying a position of disuse, a connection acting concomitantly with the raising of the platen to the sheet-inserting position to raise the paper-guide away from the paper-table to effective position for turning backwardly under the platen the bottom edge of a sheet inserted in front of the web from the delivery side of the platen, a knife adjacent the platen for severing a web passed around the platen, and means acting concomitantly with the raising of the paper-guide and platen to shift the knife downwardly away from its cutting position and into coöperative relation with the risen paper-guide to form a front extension to said paper-guide for a work-sheet inserted from the front at the back of the knife; means being included to automatically return said paper-guide to a position of disuse at the return of the platen to printing position.
29. In a typewriting machine, in combination, a rotatable platen, a paper-table below the platen, a knife adjacent the platen for severing a web passed around the platen, a paper-guide below the platen independent of the paper-table and normally occupying a position of disuse, and manually operable means for concomitantly raising the platen and paper-guide away from the paper-table to an effective sheet-inserting position and for lowering the knife into coöperative guiding relation with the raised paper-guide for turning backwardly under the platen the lower edge of a sheet inserted in front of the web at the back of the knife.
30. In a typewriting machine, in combination, a rotatable platen, a curved paper-table for guiding the work below the platen, means for raising the platen away from the paper-table to a position enabling a web to extend substantially horizontally beneath the platen and above the paper-table, and means for raising the platen to an intermediate sheet-inserting position providing for the insertion of a work-sheet from the

front below the web on the platen and above the paper-table.

31. In a typewriting machine, in combination, a rotatable platen, a curved paper-table for guiding the work below the platen, means for raising the platen away from the paper-table to a position enabling a web to extend substantially horizontally beneath the platen and above the paper-table, means for raising the platen to an intermediate sheet-inserting position providing for the insertion of a work-sheet from the front below the web on the platen and above the paper-table, and means independent of the paper-table for guiding the work-sheet as it is inserted from the front backwardly under the platen and web.

32. In a typewriting machine, in combination, a rotatable platen, a curved paper-table for guiding the work below the platen, means for raising the platen away from the paper-table to a position enabling a web to extend substantially horizontally beneath the platen and above the paper-table, means for raising the platen to an intermediate sheet-inserting position providing for the insertion of a work-sheet from the front below the web on the platen and above the paper-table, and means for holding the platen at said intermediate sheet-inserting position.

33. In a typewriting machine, in combination, a rotatable platen, a rear guide behind the platen over which a web is drawn to the introductory side of the platen, and means for guiding a front-inserted work-sheet from the delivery side of the platen below the platen and web thereon and below said rear guide for the web.

34. In a typewriting machine, in combination, a rotatable platen, a rear guide behind the platen over which a web is drawn to the introductory side of the platen, a paper-table forming a guide below the platen, means for more widely separating the paper-table and the platen to provide for the insertion of a work-sheet from the front, and means independent of the paper-table for guiding the front-inserted work-sheet from the delivery side of the platen below the platen and web thereon and below said rear guide for the web.

35. In a typewriting machine, in combination, a rotatable platen, means for supporting and guiding a plurality of plies of web to and around the lower side of the platen from the introductory side thereof, said means including a paper-table below the platen forming a guide around the platen, means for carrying carbon sheets between the plies of said web, means for raising the platen away from the paper-table to a position permitting the retraction of said carbon sheets, means for supporting the platen at an intermediate sheet-

inserting raised position free from the paper-table to provide for the insertion of a work-sheet from the delivery side of the platen at the outside of and below said web, and means independent of the paper-table for guiding said work-sheet as it is inserted.

36. In a typewriting machine, in combination, a rotatable platen, means for supporting and guiding a web below and around the platen from the introductory side thereof and including a paper-table forming a guide below the platen, means for raising the platen away from the paper-table, and means independent of the paper-table for guiding a front-inserted work-sheet from the delivery side of the platen below the platen at the outside of said web.

37. In a typewriting machine, in combination, a rotatable platen, a rear guide behind the platen over which a plurality of

plies of web may be drawn below and around the platen from the introductory side thereof, carbon-carrying means at the rear of the rear guide for supporting carbon sheets between the plies of said web, means for raising the platen to a position permitting the retraction of the carbon sheets, a paper-table forming a guide below the platen, means for increasing the distance between the platen and the paper-table to provide for the insertion of a work-sheet from the front below the platen at the outside of said web, and guiding means independent of the paper-table for directing the lower end of said front-inserted work-sheet below the platen and below said rear guide. 25 30 35
